UNITED STATES PATENT OFFICE

JOHN H. WIGGINS, OF TULSA, OKLAHOMA

STORAGE TANK FOR VOLATILE GASES AND LIQUIDS

Application filed February 15, 1928. Serial No. 254,516.

This invention relates to apparatus of the kind that are used for storing volatile liquids and gases.

One object of my invention is to provide a combined liquid storage tank and gasoline vapor recovery apparatus which are so constructed and arranged that while it is possible for gases to escape freely from the storage tank to the vapor recovery apparatus under certain conditions, it is impossible for the gases to escape from the tank or be withdrawn from the tank at such a rate as to create a vacuum in the tank that will injure the tank or cause it to collapse.

Another object is to provide a combined storage tank and gasoline vapor recovery apparatus which are so constructed and arranged that dry gases from the gas holder of the vapor recovery apparatus will be admitted to the tank automatically under certain conditions.

Another object is to provide a storage tank of the general type described in my prior U. S. Patent No. 1,645,313, dated October 11, 1927, that is equipped with a vacuum relief valve which is of such design that the downward movement of the roof of the tank is utilized to produce power which causes said valve to open and admit air or gas to the interior of the tank, either to prevent a vacuum from being created in the tank, or to increase the internal pressure of the tank.

And still another object of my invention is to provide an apparatus for storing volatile liquids and recovering the gases and vapors evolved from same, that is safe, of rugged construction, and of such design that the automatically operating valves of same do not require constant inspection, adjustment or repair to insure their remaining in an operative condition. Other objects and desirable features of my invention will be hereinafter pointed out.

Figure 1 of the drawings is a vertical transverse sectional view, illustrating one kind of storage tank that can be used in an apparatus embodying my invention, said view being taken on the line 1—1 of Figure 2.

Figure 2 is a top plan view of said tank. Figure 3 is an enlarged horizontal sectional

view of the volume-control pressure relief valve, taken on the line 3—3 of Figure 4.

Figure 4 is an enlarged vertical sectional view of the volume-control pressure relief valve, taken on the line 4—4 of Figure 2.

Figure 5 is an enlarged vertical sectional view of one of the yielding sustaining devices on the roof, taken on the line 5—5 of Figure 2.

Figure 6 is a diagrammatic view, illustrating the tank shown in Figure 1, combined with a gasoline vapor recovery apparatus.

Figure 7 is a fragmentary top plan view of a storage tank equipped with a volume-control pressure relief valve and a vacuum valve of slightly different construction and arrangement from those used in the tank illustrated in Figure 1; and

Figures 8 and 9 are vertical sectional views, taken on the lines 8—8 and 9—9 of Figure 7.

In the accompanying drawings which illustrate the preferred form of my invention, A designates a storage tank of the general type disclosed in my prior patent previously referred to, which is provided with a roof or top B that is capable of flexing upwardly and downwardly a limited distance from a horizontal plane, so as to increase and decrease the vapor space of the tank without

liability of setting up injurious strains in the roof. When the internal pressure of the tank becomes greater than the weight of the roof, due to the expansion of the gases or vapors in the tank, the roof will flex upwardly, and thus increase the volume of the vapor space in the tank. Thereafter, when the internal pressure of the tank diminishes, the roof will flex downwardly, thus automatically decreasing the volume of the gas or vapor space. Normally, the roof occupies a downwardly deflected position, as shown in full lines in Figure 1, and at such times the roof is sustained by a stationary

supporting structure inside of the tank comprising radially-disposed members C. When the internal pressure of the tank becomes greater than the weight of the roof, due to the expansion of the gases and vapors in the tank, the roof B flexes upwardly more or less, as indicated by broken lines in Figure 1.

Figure 1 of the drawings is a vertical transverse sectional view, illustrating one kind of storage tank that can be used in an apparatus embodying my invention, said view being taken on the line 1—1 of Figure 2.

Figure 2 is a top plan view of said tank. Figure 3 is an enlarged horizontal sectional

5 The roof B is provided with a volume-control pressure relief valve, designated as an entirety by the reference character D in Figure 1, that opens automatically and permits gases or vapors to escape from the tank when the roof reaches a certain position in its upward movement, and said roof is also equipped with an inlet valve or vacuum valve designated as an entirety by the reference character E in Figure 1, that opens automatically and admits air or gas to the tank when the roof reaches a certain position in its downward movement.

10 As previously stated, two of the objects of my present invention are as follows:

15 (1) To combine a storage tank of the general type referred to with a gasoline vapor recovery apparatus in such a way that the gases or vapors can pass from the tank to said recovery apparatus without liability of the tank being injured or damaged, due to the gases or vapors being withdrawn from same at such a rate as to create a vacuum in the tank; and

20 (2) To combine such a tank with such an apparatus in such a way that dry gases, or gases stripped of gasoline vapors, can pass automatically from the gas holder of the recovery apparatus into the tank under certain conditions, as, for example, when the internal pressure of the tank drops below a certain approximate degree, or when the internal pressure of the tank becomes diminished, due to withdrawing liquid from the

25 tank.

30 Accordingly, in Figure 6 of the drawings I have illustrated the tank A combined with a gasoline vapor recovery apparatus which comprises a device F of any suitable type or kind for stripping gasoline vapors or for removing gasoline vapors from the gases which escape from the tank A when the volume-control pressure relief valve D opens, a gas holder G combined with the stripping device F in such a way that the dry gases will pass from the device F into the gas holder G, and a return pipe H leading from the gas holder G to the vacuum valve E for admitting dry gases to the tank A when said 35 vacuum valve opens. It is immaterial, so far as my broad idea is concerned, what type or kind of inlet valve or vacuum valve E is used to admit gases to the tank at a certain point in the downward movement of the roof, except that the movement of the roof must operate this intake valve, but I prefer to equip the tank with an inlet valve or vacuum valve of such design that the downward movement of the roof is used to produce power which causes said valve to open. Accordingly, when such a valve is used, it is preferable to equip the roof B with a plurality of yielding sustaining devices 1 that project downwardly from the underside of the roof and co-operate with the supporting

40 structure C to hold the roof spaced slightly away from said supporting structure when the internal pressure of the tank is equal to or slightly less than the weight of the roof, said devices 1 being capable of yielding, and thus permitting the roof to move downwardly, below its normal position, towards the supporting structure C whenever a partial vacuum exists in the tank, as, for example, when liquid is being withdrawn from the tank. 45 This slight downward movement of the roof from its normal position, represented in full lines in Figure 1, towards the supporting structure C is utilized to open the vacuum valve or inlet valve E.

50 The particular design or construction of the yielding sustaining devices 1 on the roof is immaterial, but they are herein illustrated as consisting of spring-pressed devices, each of which comprises a plunger 1 (see Figure 5), that projects upwardly through a tubular housing 2 connected to the top side of the roof and combined with an expansion spring 3 that is interposed between a collar or abutment 4 on the plunger and a co-operating abutment 5 that is adjustably mounted in the housing 3. The abutment 5 is screwed into an internally screw-threaded portion at the upper end of the housing 3 and is attached to a sleeve 5^a that is accessible from the upper end of the housing after the cap 3^a of the housing has been removed, said sleeve 5^a being adapted to be turned or rotated so as to raise or lower the spring abutment 5, and thus vary the tension of the spring 3. In the operation of fabricating the roof B or joining the plates that constitute the roof, said plates are sustained by the supporting structure C. After the plates have been connected together so as to form an imperforate diaphragm which is connected at its peripheral edge to the side wall of the tank A, the springs 3 that are associated with the plungers 1 are set at such a tension that said plungers will exert sufficient force against the supporting structure C to raise the roof off said supporting structure, as shown in Figure 1. The vacuum valve or inlet valve E is composed of a gas-tight housing 6 attached to the top side of the roof, an annular valve seat 7 inside of said housing that surrounds an inlet opening 8 formed in the portion of the roof B that constitutes the bottom of said housing, and a horizontally-disposed valve element 9 arranged to act on the valve seat 7 and provided with a depending stem 10 that is arranged in alignment with one of the members C of the supporting structure. If desired, the valve seat 7 can be constructed in the form of an annular trough that contains a sealing liquid which co-operates with a depending annular flange 9^a on the valve element 9 to form a liquid sealed valve, but it is not essential that the inlet valve E be of the liquid sealed type. The

return pipe H that leads from the gas holder G of the vapor recovery apparatus communicates with the interior of the housing 6, thus causing the valve element 9 to be held tightly against its seat 7 by the pressure of the dry gases in the return pipe H. However, whenever the roof B moves downwardly beyond a certain point, for example, from the position shown in full lines in Figure 1, the stem 10 of the valve element 9 is brought into engagement with the member C of the supporting structure with which it aligns, thereby causing said valve element to remain at rest while the roof B continues to move downwardly, thus effecting the unseating of said valve element. As soon as said valve element unseats or opens, dry gas will pass into the tank from the return pipe H, and thus raise the internal pressure of the tank, or supply sufficient gas to the tank to prevent a destructive vacuum from being created in the tank. As soon as the roof starts to rise or move upwardly back to its normal position, the valve element 9 closes automatically, and thereafter remains in its closed condition until the roof again moves downwardly to such a point as to effect the unseating of said valve element. With an inlet valve or vacuum valve of the construction above described a very slight partial vacuum inside of the tank A causes said valve to open automatically, notwithstanding the fact that there is considerable pressure in the housing 6 which is exerted on the valve element 9 in a direction tending to hold said valve element against its seat, due to the fact that a force tending to unseat or open the valve is exerted on the roof of the tank in a direction tending to draw said roof and the valve seat 7 downwardly away from the valve element 9 which is held at rest by the supporting structure C against which the stem 10 of the valve bears. While I have herein illustrated the vacuum valve or inlet valve E as being held seated by a gaseous medium under pressure, I wish it to be understood that any other suitable means can be used to hold said valve seated, so long as the valve is mounted or combined with the roof of the tank in such a way that the downward movement of the roof beyond a certain point is used to create pressure that causes said valve to open.

The volume-control pressure relief valve D is preferably constructed in the manner illustrated in Figure 4, and comprises a valve element 11 arranged on the underside of an annular valve seat member 12 which is positioned inside of a gas-tight housing 13 that is attached to the top side of the roof B of the tank in alignment with a gas outlet 14 in said roof, the interior of the housing 13 being connected by a pipe 15 with the gasoline vapor stripping device F of the recovery apparatus. The valve element 11 is rig-

idly connected to a stem 16 that passes upwardly through a guide 17 on the valve seat member, and a spring 18 is interposed between the guide 17 and a stop 19 on the valve stem 16, so as to exert upward pressure on the valve element 11 tending to move it towards its seat. If desired, the valve element 11 and the seat with which it co-operates can be constructed in such a way as to form a liquid sealed valve, the valve element herein illustrated being provided with an annular trough 11^a that holds a sealing liquid in which the lower edge portion of the valve seat member 12 is normally submerged. The valve stem 16 has pivotally connected to same a depending link 20 which is provided adjacent its lower end with a cross piece 21 that is arranged beneath one of the members C of the supporting structure inside of the tank. During the upward movement of the roof from its depressed towards its elevated position, the cross piece 21 comes into engagement with the supporting structure C, thereby arresting the upward movement of the valve element 11 and causing it to remain at rest while the roof and the valve seat member 12 carried by the roof continue to move upwardly, which action of course results in unseating the valve element 11. As soon as said valve element has been unseated or opened, the gases or vapors escape from the vapor space of the tank A through the pipe 15 into the stripping device F, thereby relieving the internal pressure of the tank and preventing the roof from being subjected to destructive or injurious strains, the roof moving downwardly to its normal position as the volume of the gases in the tank diminishes, and finally coming to rest in the position shown in full lines in Figure 1, when the internal pressure of the tank becomes less than the weight of the roof.

In Figure 7, 8 and 9 of the drawings I have illustrated another kind of storage tank that can be used with an apparatus of the kind illustrated in Figure 6, which storage tank is equipped with a volume-control pressure relief valve and a vacuum or inlet valve mounted on the roof B' of the tank adjacent the side wall of the tank. The flexing of the roof of the upward and downward movement of the roof is used to produce power that causes said valves to open, but the mechanism that is actuated by the movement of the roof is located adjacent the center of the roof and is connected by means of rods or other suitable actuating devices with levers or similar elements associated with the valves. In the tank shown in Figures 7 to 9 the vacuum valve or inlet valve is so constructed and arranged that it will admit air or dry gases to the tank, even though the tank is under pressure. In other words, the roof B' of the tank is normally held in a position with its central portion out of contact with the supporting struc-

ture C by the upward pressure which the gases inside of the tank exert on the underside of the roof. Whenever this internal pressure drops below a certain approximate degree, the roof will move downwardly slightly, and thus cause the vacuum valve or inlet valve to open. It will thus be seen that it is immaterial, so far as my invention is concerned, whether a partial vacuum or a positive pressure exists in the tank at the time the inlet valve opens. In Figures 7, 8 and 9 the reference character D' designates as an entirety the volume-control pressure relief valve, and the reference character E' designates as an entirety the vacuum valve or inlet valve. The valve D' comprises a valve element 11 that co-operates with a valve seat 12, and said valve seat and valve element are arranged inside of a gas-tight housing 13 which is connected by means of a pipe 15 with the gasolene vapor stripping device F of the recovery apparatus, said housing 13 communicating with a gas outlet 14 in the roof B' of the tank, and the spring-actuated stem 16 of the valve element 11 being arranged in contact with the horizontal arm of a bell crank lever 22 whose vertical arm is connected by means of a rod 23 or other suitable device with an actuating mechanism, hereinafter described, that is arranged adjacent the central portion of the roof B' of the tank. The vacuum valve or inlet valve E' (shown in Figure 9) also comprises a valve element 9 that co-operates with a seat 7, and said valve element and valve seat are arranged inside of a housing 9^a on the roof of the tank that communicates with an inlet opening 8 in said roof, the stem 10 of the valve element being arranged in contact with the horizontal arm of a bell crank lever 24 whose vertical arm is connected by means of a rod or other suitable device 25 with the actuating mechanism previously referred to located adjacent the center of the roof of the tank. This actuating mechanism is herein illustrated as comprising two bell crank levers 26 and 27 pivotally mounted in any suitable manner on the upper side of the roof B' of the tank. The vertical arm of the bell crank lever 26 is fastened to the rod 23 associated with the volume-control pressure relief valve D', and the horizontal arm of said bell crank lever is pivotally connected to a depending link 20 provided with a cross piece 21, which is adapted to engage one of the supporting members C on the inside of the tank during the upward movement of the roof, and thus cause the bell crank lever 26 to rock in a direction to cause the bell crank lever 22 to unseat or open the valve element 11 of the volume-control pressure relief valve D'. The bell crank lever 27 that is associated with the inlet valve or vacuum valve E' has its vertical arm connected to the rod 25, as shown in Figure 9. Attached to the hori-

zontal arm of the bell crank lever 27 is a device 10^a that is arranged in alignment with one of the supporting members C. Consequently, when the roof B' moves downwardly beyond a certain approximate position, the device 10^a, associated with the bell crank lever 27, will come in contact with the supporting member C, and if the roof thereafter continues to move downwardly, the bell crank lever 27 will be rocked in a direction to cause the bell crank lever 24 to open or unseat the element 9 of the inlet valve E'. If desired, the roof B' of the tank can be equipped with a vent valve 28, shown in Figure 8, that opens automatically and establishes communication between the atmosphere and the vapor space of the tank when the volume of the gases or vapors in the tank reaches a dangerous degree. This vent valve 28 is similar in general design to the volume-control pressure relief valve E, used in the tank illustrated in Figure 1, and the stem 16^a of said valve is pivotally connected to a link 20^a which is provided at its lower end with a cross piece 21^a arranged so that it will engage a part of the supporting structure C, and thus cause the vent valve 28 to open, in the event the roof B' moves upwardly past a certain point, when the volume-control pressure relief valve D' is open. As shown in Figure 8, the cross piece 21 that is associated with the link 20, and the cross piece 21^a that is associated with the link 20^a, can be adjustably combined with said links so as to permit said cross pieces to be arranged in different positions to cause the volume-control pressure relief valve D' and the vent valve 28 to open at different times or at different points in the upward movement of the roof B', the means herein illustrated for effecting the adjustment of said cross pieces consisting of a series of holes 29 in each of the links adapted to receive a removable pin 30 that holds the cross piece in a certain position on the link. The rods or other actuating devices 23 and 25 that are associated with the valves D' and E', respectively, extend radially from the actuating mechanism at the center of the roof of the tank over supporting devices 31, and if desired, said rods can be provided with turn-buckles 32 that can be adjusted so as to accurately control the opening and closing of the vacuum-control pressure relief valve and the inlet valve. In an apparatus of the construction above described, there is no danger of the gases being withdrawn from the storage tank into the stripping device F of the vapor recovery apparatus at such a rate as to produce a dangerous vacuum in the storage tank that might result in said tank collapsing, due to the fact that the movement of the flexible roof of the tank is used to control the opening and closing of the volume-control pressure relief valve which establishes and cuts off communication between the vapor space of the

storage tank and the stripping device F of the vapor recovery apparatus. In other words, the escape of the gases from the storage tank into the stripping device F causes the roof of the storage tank to move downwardly, with the result that the valve D will close automatically approximately before a partial vacuum is created in the tank. Another desirable feature of such an apparatus is that stripped gases from the recovery apparatus are admitted automatically to the vapor space of the storage tank whenever a partial vacuum is created in the tank during the operation of withdrawing liquid for same, or whenever the internal volume of the tank drops below a certain approximate degree. While I have herein illustrated the vacuum valve or inlet valve as forming part of an apparatus in which the unseating or opening of said valve causes dry gases to be admitted to the storage tank, I wish it to be understood that said valve is not restricted to use in an apparatus of the particular type herein illustrated, as one feature of my present invention consists of a storage tank provided with a flexible roof and equipped with a vacuum valve or inlet valve which is so constructed and arranged that the downward movement of the roof is utilized to produce power that causes said valve to open. An apparatus of the construction herein described enables volatile liquids to be stored with safety, the apparatus is of very rugged construction, and it is equipped with automatically-operating valves that do not require constant inspection or repair to keep them in an operative condition, the valves being held seated or closed by pressure which is high enough to eliminate the possibility of their opening accidentally, and being unseated or moved into their open position by a positive pressure produced by the up and down movement of the roof.

Having thus described my invention, what I claim as new and desire to secure by Letters Patent is:

1. An apparatus for the purpose described, comprising a storage tank for liquid provided with a roof that is capable of flexing upwardly and downwardly to increase or decrease the volume of the vapor space of the tank under certain conditions, means operated by the movement of the roof for permitting gases to escape from the tank when the roof reaches a certain approximate position during its upward movement, a pipe attached to the roof and leading from a supply of gas, an inlet valve held seated by the gas in said supply pipe for admitting gas to the tank, and means operated by the movement of the roof for causing said inlet valve to open in the event the roof moves downwardly beyond a certain approximate position.

2. An apparatus of the kind described, comprising a storage tank adapted to receive vol-

atile liquids and provided with a roof that is capable of flexing downwardly from a certain approximate normal position, a gas supply pipe connected with the roof and leading from a supply of gas under pressure, an inlet valve on the roof that is normally held seated by the pressure in said supply pipe, and means whereby the downward movement of the roof from its approximate normal position causes said inlet valve to open automatically and admit gas to the tank from said supply pipe.

3. A tank for storing volatile liquids and gases provided with a flexible roof that is adapted to flex upwardly and downwardly relatively to an intermediate horizontal plane so as to increase and decrease the vapor space of the tank, an inlet valve that controls an opening through which a gaseous medium is admitted to the tank, a stationary structure arranged inside of the tank under the roof, yielding devices on the roof adapted to co-act with said structure to normally hold the roof spaced away from said structure, and means for utilizing the downward movement of the roof beyond its said normal position to produce power that is exerted on said inlet valve in a direction to open the same.

4. A tank for storing volatile liquids and gases provided with a flexible roof that is adapted to move downwardly, a structure inside of the tank, normally spaced away from the underside of the central portion of the roof that is adapted to support the roof under certain conditions, an inlet valve in the roof that is normally held seated, and a device that co-operates with said supporting structure during the downward movement of the roof towards said supporting structure to cause said valve to open.

5. In a storage tank of the type that is provided with a flexible roof which is adapted to flex upwardly and downwardly relatively to an intermediate horizontal plane to vary the volume of the vapor space of the tank, a stationary roof supporting structure arranged inside of the tank on the underside of the roof, a valve mounted on the roof, means for holding said valve seated, and a means adapted to co-act with said structure and rendered operative by the flexing of the roof, for positively unseating said valve.

6. In a storage tank of the type provided with a roof that is adapted to flex upwardly and downwardly to vary the volume of the vapor space of the tank, an inlet valve on the roof, a seat for said valve arranged underneath the same, and a part on the valve that co-operates with a means on the inside of the tank for arresting the movement of the valve relatively to its seat so as to cause the valve to open during the downward movement of the roof.

7. A storage tank provided with a roof

- that is capable of flexing upwardly and downwardly relatively to an intermediate horizontal plane to increase or decrease the volume of the vapor space of the tank under 5 certain conditions, a stationary structure arranged inside of the tank beneath the roof, and a resilient means carried by the roof and adapted to co-act with said stationary structure, for normally supporting said roof.
10. 8. In a storage tank of the type that is provided with a roof which is adapted to flex upwardly and downwardly relatively to an intermediate horizontal plane to vary the volume of the vapor space of the tank, a reciprocating outlet valve for venting the tank or relieving the internal pressure of same, a seat for said valve carried by the roof and arranged above the valve, and a means rendered operative by the upward flexing of the 15 roof for exerting a direct pull on said valve so as to open the same.
15. 9. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, a seat for said valve carried by the roof and adapted to 20 move with same, a means for holding said valve seated, arranged on the exterior of the tank, and a means rendered operative by the upward flexing of the roof for opening said valve.
25. 10. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, a seat for said valve arranged above the valve and carried by the roof, a spring for holding said valve seated, arranged above the valve, and a means 30 for unseating the valve that is adapted to co-act with a part on the inside of the tank during the upward flexing of the roof.
35. 11. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular seat for said valve arranged above the valve and carried by the roof, a means that normally exerts pressure on said valve in a direction tending to hold it against said seat, and a means for exerting a direct pull 40 on said valve in a direction to open the same during the upward movement of the roof.
45. 12. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 50 seat for said valve arranged above the valve and carried by the roof, a means that normally exerts pressure on said valve in a direction tending to hold it against said seat, and a means for exerting a direct pull on said valve in a direction to open the same during the upward movement of the roof.
55. 13. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, a seat for said valve arranged above the valve and adapted to move with the roof, and a means for exerting a direct pull on said valve to open the same during the upward movement of the roof, comprising a device suspended from the valve and provided with a part that is adapted to engage a stationary means located on the underside of the roof.
60. 14. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, a seat for said valve arranged above the valve and carried by the roof, a stem projecting upwardly from the top side of the valve, a guide for said stem arranged above the valve, a means that co-acts with said stem to hold the valve seated, and a means that is rendered operative by the upward flexing of the roof for opening the valve.
65. 15. In a storage tank of the type that is provided with a roof which is adapted to flex upwardly and downwardly relatively to an intermediate horizontal plane to vary the volume of the vapor space of the tank, an outlet valve for venting or reducing the internal pressure of the tank, a seat for said valve arranged above the valve and adapted to move with the roof, a means for guiding 70 said valve located outside of the gas space of the tank, and a device suspended from the valve and adapted to co-act with a stationary part inside of the tank to unseat the valve during the upward movement of the roof.
75. 16. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, a seat for said valve arranged above the valve and adapted to move with the roof, a means arranged on the outside of the gas space of the tank for holding said valve seated, and a depending part on said valve provided with an adjustable means that is adapted to co-act with a means inside of the tank for 80 causing said valve to move away from its seat during the upward movement of the roof.
85. 17. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 85 seat for said valve arranged above the valve and carried by the roof, a means that normally exerts pressure on said valve in a direction tending to hold it against said seat, and a means for exerting a direct pull on said valve in a direction to open the same during the upward movement of the roof.
90. 18. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 95 seat for said valve arranged above the valve and carried by the roof, a means that normally exerts pressure on said valve in a direction tending to hold it against said seat, and a means for exerting a direct pull on said valve in a direction to open the same during the upward movement of the roof.
95. 19. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 100 seat for said valve arranged above the valve and carried by the roof, a means that normally exerts pressure on said valve in a direction tending to hold it against said seat, and a means for exerting a direct pull on said valve in a direction to open the same during the upward movement of the roof.
105. 20. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 105 seat for said valve arranged above the valve and carried by the roof, a means that normally exerts pressure on said valve in a direction tending to hold it against said seat, and a means for exerting a direct pull on said valve in a direction to open the same during the upward movement of the roof.
110. 21. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 110 seat for said valve arranged above the valve and carried by the roof, a means that normally exerts pressure on said valve in a direction tending to hold it against said seat, and a means for exerting a direct pull on said valve in a direction to open the same during the upward movement of the roof.
115. 22. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 115 seat for said valve arranged above the valve and carried by the roof, a means that normally exerts pressure on said valve in a direction tending to hold it against said seat, and a means for exerting a direct pull on said valve in a direction to open the same during the upward movement of the roof.
120. 23. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 120 seat for said valve arranged above the valve and carried by the roof, a means that normally exerts pressure on said valve in a direction tending to hold it against said seat, and a means for exerting a direct pull on said valve in a direction to open the same during the upward movement of the roof.
125. 24. In a storage tank of the type that is provided with a roof which is adapted to flex upwardly and downwardly relatively to an intermediate horizontal plane to vary the volume of the vapor space of the tank, an outlet valve for venting the tank or reducing the internal pressure of same, an annular 125 seat for said valve arranged above the valve and carried by the roof, a means that normally exerts pressure on said valve in a direction tending to hold it against said seat, and a means for exerting a direct pull on said valve in a direction to open the same during the upward movement of the roof.

seat for said valve arranged above the valve and adapted to move with the roof, a stem projecting upwardly from the top side of said valve, a guide through which said stem passes, a spring mounted on said stem between said guide and an abutment on the stem for normally holding the valve seated, a depending part pivotally connected to the underside of the valve, and a member on said depending part that is adapted to operate with a means inside of the tank for causing said valve to separate from its seat during the upward movement of the roof.

JOHN H. WIGGINS.
